UNITED STATES PATENT OFFICE.

PERCY ALWEN, OF VERNON, BRITISH COLUMBIA, CANADA.

LAMP-SUPPORT.

1,299,533.

Specification of Letters Patent.

Patented Apr. 8, 1919.

Application filed November 20, 1917. Serial No. 202,962.

To all whom it may concern:

Be it known that I, PERCY ALWEN, a citizen of the United States, residing at Vernon, in the county of Yale-Cariboo and Province 5 of British Columbia, Canada, have invented certain new and useful Improvements in Lamp-Supports, of which the following is a specification.

The present invention relates to lamp supports, and more particularly to that type adapted to support lamps on motor vehicles, motorcycles, and the like.

An object of the present invention is to provide a lamp support which is resilient and adapted to absorb shock to prevent injury and undue jarring of the lamp, to provide a support which comprises relatively few parts; a support which may be easily and quickly applied to motor vehicles and 20 motorcycles; and a support which not only absorbs shock incident to vibration of the vehicle but also absorbs recoil shock and yieldingly maintains the lamp in adjusted position.

25 The above and various other objects and advantages of this invention will be in part described and in part understood from the following detailed description of the present preferred embodiment of this invention, the 30 same being illustrated in the accompanying drawing, wherein:

Figure 1 is a front elevation of a resilient lamp support constructed according to the present invention, showing the support retaining a lamp upon the handle bars of a motorcycle or the like.

Fig. 2 is a side elevation of the same.

Fig. 3 is an enlarged longitudinal section through one side of the support.

40 Fig. 4 is a front elevation of a modified form of the support.

The support of this invention comprises a pair of similarly formed members each comprising a cylinder or socket portion 10 closed at its lower end by a wall 11 and having a detachable cap 12 upon its upper end. Slidably in the cylinder is a rod 13, the same passing through an aperture in the cap 12 and telescoping into the cylinder and being 45 of reduced diameter to accommodate a helical spring 14 which surrounds the rod 13. The upper end of the spring 14 bears against the cap 12 and the lower end of the spring 50 is seated against an annular flange or head 15 formed upon the lower end of the rod 13.

The head 15 fits snugly in the cylinder 10 and holds the lower end of the rod from lateral vibration. The cap 12 fits closely about the upper portion of the rod 13 and prevents the lateral vibration thereof. The cylinder 10 is provided in its lower end with a relatively strong helical spring 16 resting on the bottom wall 10 and bearing at its upper end against a wear plate 17 fitting against head 15 and which is preferably 60 formed from metal. The upper end of the rod 13 is provided with an inwardly extending attaching ear 18 adapted to be secured, riveted or otherwise suitably secured against the adjacent side of a lamp A.

70 The cylinder 10 is carried upon a bracket arm 19 which is flared at its forward end and grooved to the configuration of the adjacent side of the cylinder 10, and provided with a collar 20 substantially in axial alignment with the arm 19 and through which the cylinder 10 is adapted to fit. The cylinder 10 may be welded or otherwise suitable secured to the flaring forward end of the arm 19. A clip 21, in the form of an overturned 80 metallic strip is slidably mounted upon the rear end of the arm 19 and is adapted to engage at its free ends upon a support engaging clip 22, the latter being adapted to encircle the handle bar B of a motorcycle 85 or the like. The free ends of the support engaging clip 22 are brought together beneath the free ends of the clip 21 and are adapted to be clamped thereto by a clamping screw 23 which passes through the ears 90 or free ends of both of the clips 21 and 22 and simultaneously binds the clips upon their respective elements.

95 The structure above described employs a pair of supporting members which are adapted more particularly for attachment in front of a vehicle. In Fig. 4 a slight modification is shown wherein the bracket is adapted more particularly for attachment to the side of a vehicle or the like. In this latter instance the cylinders 24 are made integral at their lower ends by the formation of a main frame or body part which is substantially U-shaped. The supporting arm 25 extends laterally from this double support and carries upon its outer end a U-shaped socket piece 26 which is semi-cylindrical in cross-section and is bent longitudinally into U-shape to receive therein the body 24. Tongues 27 are formed in pairs near the 100 105 110

upper ends of the socket piece at the opposite edges thereof and are adapted to embrace the upper ends of the bracket 24 similar to the engagement of the tongues 20 of 5 the arm 19. The bracket arm 25 is provided with an attaching plate 28 on its inner end adapted to be secured by bolts or the like to the side of the vehicle.

It will be noted from Fig. 2 that the outer 10 end of the arm 19 is formed into a substantially semi-cylindrical socket into which the cylinder 10 is seated, the lower end of the socket, designated at 29, engaging beneath the lower end of the cylinder.

15 When the device is in use the lamp A is secured between the attaching ears 18 and supported upon the rods 13. The springs 16 yieldingly support the lamps and when the vehicle is subjected to jarring or vibration 20 the springs 16 are compressed and the upper springs 14 expand. The upper springs prevent the sudden recoil of the lower springs 16 and thus prevent undue jar from the vehicle to the lamps.

25 It is of course understood that various changes and modifications may be made in the details of construction of the foregoing embodiment of the present invention without departing from the spirit thereof, such 30 changes and modifications being restricted only by the scope of the following claims.

I claim:

1. In a lamp support, the combination of 35 a cylindrical member, a supporting bracket for said cylindrical member comprising a bracket arm, a flared portion formed on the outer end of the arm and grooved longitudinally to snugly fit said cylindrical member, a collar formed integrally with said grooved 40 flared portion and embracing said cylindrical member, the lower end of said flared portion being curved transversely to fit be-

neath the lower end of the cylindrical member.

2. In a lamp support, the combination of 45 a cylindrical member, a supporting bracket for said cylindrical member comprising a bracket arm, a flared portion formed on the outer end of the arm and grooved longitudinally to snugly fit said cylindrical member, a collar formed integrally with said grooved flared portion and embracing said cylindrical member, the lower end of said flared portion being curved transversely to fit beneath the lower end of the cylindrical 50 member, a rod slideable in the cylinder and adapted for attachment at its upper end to a lamp, said rod having a head upon its lower end fitting within the cylinder, and springs arranged at the opposite ends of the cylinder 55 and engaging the upper and lower sides of said head for yieldably holding the rod from vertical movement.

3. In a lamp support, the combination of 60 a cylindrical member bent to form substantially a U-shape, rods yieldably supported by the parallel portion of the cylindrical member and adapted for connection with a lamp, a supporting bracket for said member comprising a bracket arm, a substantially 65 U-shaped portion formed upon the outer end of said arm, and grooved to snugly fit said substantially cylindrical member, collars formed integrally upon said grooved member near the free end thereof and embracing the substantially parallel portions 70 of the substantially cylindrical member, the bight portion of said bracket carried member having its upper surface concaved or grooved for receiving therein the lower portion of the bight portion of the U-shaped 75 substantially cylindrical member.

PERCY ALWEN.
